UNITED STATES PATENT OFFICE

163,728

CORN TRAY

William H. Youngerman, Chicago, Ill., assignor to Merchants Sales Corp., Chicago, Ill., a corporation of Illinois

Application April 28, 1950, Serial No. 9,560

Term of patent 14 years

(Cl. D44—10)

To all whom it may concern:

Be it known that I, William H. Youngerman, a citizen of the United States, residing at Chicago, State of Illinois, have invented a new, original, and ornamental Design for Corn Tray, of which the following is a specification, reference being had to the accompanying drawing, forming a part hereof.

Fig. 1 is a top plan view of a corn tray, embodying my new design;

Fig. 2 is a side elevational view;

Fig. 3 is a bottom plan view; and

Fig. 4 is an end elevational view thereof.

I claim:

The ornamental design for a corn tray, substantially as shown.

WILLIAM H. YOUNGERMAN.
